UNITED STATES PATENT OFFICE.

IGNATIUS GERACI, OF BALTIMORE, MARYLAND.

DESIGN FOR A TAILOR'S GAGE.

SPECIFICATION forming part of Design No. 21,568, dated May 24, 1892.

Application filed April 28, 1892. Serial No. 431,063. Term of patent 14 years.

To all whom it may concern:

Be it known that I, IGNATIUS GERACI, a subject of the King of Italy, (but have made declaration of my intention of becoming a citizen of the United States,) residing at Baltimore, in the State of Maryland, have invented and produced a new and original Design for Tailors' Gages, of which the following is a specification.

This design has for its object to provide a novel and ornamental tailor's gage which presents a distinguishing and characteristic appearance to the eye.

The design consists in a tailor's gage composed of a flat plate having a pear-shaped body, a contracted neck, a pointed or V-shaped end, and a tapered branching arm provided with curved edges, and an angular or V-shaped projection in proximity to the inner edge of the contracted neck.

The design is illustrated by the accompanying drawing, in which the figure is a perspective view of the tailor's gage.

In the drawing, the numeral 1 indicates the pear-shaped body; 2, the contracted neck; 3, the pointed or V-shaped end, and 4 the tapered branching arm provided with the curved edges 5 and 6 and the angular or V-shaped projection 7 in proximity to the inner edge of the contracted neck.

What I claim is—

The design for a tailor's gage, substantially as shown and described.

In testimony whereof I have hereunto set my hand in presence of two subscribing witnesses.

IGNATIUS GERACI.
